UNITED STATES PATENT OFFICE

2,571,050

ADJUSTABLE BENCH STOP

Joseph U. Micheli, Rosemead, Calif.

Application April 5, 1948, Serial No. 19,049

1 Claim. (Cl. 144—306)

1

This invention relates to a stop or work-retaining device for use on a bench such as is used by a carpenter or mechanic, and has as an object the provision of a simple, effective, and easily manipulated stop against which pieces of work material may be abutted during such operations as planing, gauging, chiseling, or filing, in which it is desired to hold the work material stationary against a pressure having a horizontal component.

A further object of the invention is to provide a stop which may be permanently secured to a bench and may be adjusted to an abutting position when in use and to a position flush with or below the bench surface when not in use so as not to interfere with the use of the bench for other work.

Another object of the invention is to provide a stop which may be held by friction of its parts in either of the above-described positions and so is free of catches, ratchets, or threaded devices requiring manipulation to hold it in or release it from said position, and which may be moved from one of said positions to the other by simple pressure on the abutting member.

Still another object of the invention is to provide a stop which may be easily adjusted to abut a piece of work material at any selected height above the surface of the bench within the limits of the stop's adjustability.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred forms within the scope of my invention as set forth in the claim.

Referring to the drawings:

Figure 1 is a side elevational view of a stop embodying the principles of this invention, shown installed in a work bench, the bench being shown in section to illustrate the manner of installation.

Figure 2 is a top plan view of the stop shown in Figure 1.

Figure 3 is a longitudinal vertical sectional view, the plane of section being indicated by the lines 3—3 of Figure 2, with the direction of view as indicated.

Figure 4 is a transverse vertical sectional view, the plane of section being indicated by the lines 4—4 of Figure 3, with the direction of view as indicated.

2

Specifically describing that embodiment of my invention which has been chosen for illustration and description herein, my adjustable bench stop comprises a plate 6 which may be countersunk in a suitable depression 7 partly surrounding a slot 8 in a bench 9 so that the upper surface 10 of the plate is flush with the upper surface 11 of the bench. The plate 6 is provided with countersunk holes 12 at its corners for securing the plate 10 in the depression 7 by such means as screws 13. Extending downwardly from the plate 6 are spaced parallel ears or lugs 14 which may extend through the slot 8 to a position below the bench.

A dog 15 is pivotally mounted on a shaft 16 between the ears 14 and has a hub portion 17, a short rearward arm 18 extending sharply upwardly towards the plate 6, and a longer forward arm 19 extending upwardly to a more gradual inclination and forwardly to a position beyond the plate 6. The distal end of the arm 19 has a head 20 with a flat upper surface 21 and a forward margin 22 which may be tapered outwardly to a horizontal edge and indented to form teeth 23. The slot 8 also extends forwardly of the plate 6 to 25 permit the head 20 to reach and rise above the upper surface 11 of the bench 9. The relative length and angulation of the arms 18 and 19 is such that when the surface 21 of the head 20 is flush with the surface 10 of the plate 6, the arm 18 comes into contact with the under side of the plate 6 and prevents further depression of the surface 21.

Upward disposition of the surface 21 above the surface 10 is adjustably controlled by a set screw 24 in the plate 6, which makes contact with a shoulder 25 on the arm 19. The set screw 24 is preferably threaded in a thickened portion or lug 26 on the plate 6 so that it may have adequate threaded engagement with the plate and a substantial range of adjustability without at any time extending above the surface 10.

To retain the dog 15 in any position between the limits imposed by contact of the arm 18 with the plate 6 or contact of the set screw 24 with the shoulder 25, a friction braking device is provided, as indicated generally at 27, reactive between the hub portion 17 of the dog 15 and one of the ears 14. Preferably the hub portion 17 has a bore 28 extending parallel to the shaft 16 and enclosing a compression spring 29 and partly enclosing a friction member 30, which may be a disc or plug slidably fitting in the bore 28. The friction member 30 is pressed by the spring 29 into frictional engagement with the inner surface of the adjacent ear 14 to provide a light braking action on movement of the dog 15. It

will be understood that the bore 28 might extend through the hub portion 17 and have friction members at each of its ends, but I have found that one friction member provides adequate braking.

To place my adjustable bench stop in active position, it is only necessary to pull upwardly with the tip of a finger on the arm 19 so as to raise the margin 22 of the head 20 above the bench surface 11, as shown in broken lines in Figure 1. Finger pressure will suffice to overcome the braking of the friction member 30, which will thereafter hold the head 20 in raised position. A piece of work material, such as a block of wood, indicated at 31 in Figure 1, may then be placed on the surface 11 of the bench with one margin in abutment with the margin 22 of the head 20. Pressure of a tool on the work material in the direction of the head 20 will tend to cause the teeth 23 to engage the work material to prevent side slippage. The height at which the margin 22 engages the work material may be regulated by adjustment of the set screw 24. The margin 22 may be lowered to the level of the bench surface 11 by finger pressure on the surface 21, and the arm 18 will stop this lowering movement when the surfaces 10, 11, and 21 are flush.

Carpenters and mechanics may arrange the slots 8 in their benches to suit their own convenience and ideas. If the portion of the slot 8 extending forwardly of the plate 6 is no larger than is required to accommodate the head 20, the surface 21 will close the slot when the head is depressed and will prevent loss of small objects, such as bolts and nuts, through the slot. A carpenter may prefer to have the slot 8 longer than the head 20, as illustrated, and drill a hole through the bench in order to provide an opening through which chips and shavings from the work material may fall and thus prevent clogging up.

I claim:

A bench stop for use with a work bench hav-

ing a slot to receive said bench stop, comprising a plate, means for securing said plate to said work bench so as to leave exposed a portion of said slot, spaced ears depending from said plate adjacent one end thereof into said slot, a dog pivotally mounted between said ears for movement in a vertical plane, said dog having a first arm extending beyond the opposite end of said plate into the exposed portion of said slot and inclined so that its distal end may emerge upwardly from said slot, a head on said distal end, work-engaging means on the edge of said head remote from said plate whereby pressure of work-material against said engaging means urges said dog to rotate about its axis of pivotal connection to said plate in that direction in which said head would rise higher above said plate, a second arm on said dog extending oppositely to said first arm and inclined upward to engage said plate when said first arm is depressed so as to then limit the depression of said first arm, a set screw threaded in said plate and engageable with said first arm adjacent the distal end thereof to regulate the height to which said distal end may extend above said plate, and a spring-urged friction member between the adjacent surfaces of the hub portion of said dog and one of said ears.

JOSEPH U. MICHELI.
